UNITED STATES PATENT OFFICE

2,504,805

METHOD OF AND APPARATUS FOR APPLYING SLURRIES TO STRUCTURAL SURFACES

Samuel Clipson, London, England

Application February 4, 1948, Serial No. 6,233
In Great Britain July 15, 1946Section 1, Public Law 690, August 8, 1946
Patent expires July 15, 1966

3 Claims. (Cl. 117—104)

1

This invention is concerned with the application to structural surfaces, such as ceilings and walls, of slurries of plaster, cement, mortar and the like.

In accordance with the invention the slurry is mechanically applied by a method which consists in supplying the slurry under pressure along a barrel to the vicinity of an end nozzle thereon affording an abruptly restricted outlet, and in subjecting the slurry in that vicinity to the action of a stream of pressure air or gas to compact and densify the slurry before it leaves the said nozzle outlet.

Apparatus for practising the method comprises a barrel having at one end an inlet for the supply of slurry under pressure and at the other end a discharge nozzle with an abruptly restricted outlet, and means manually adjustable axially of the barrel for introducing pressure air or gas into the barrel in advance of the said abruptly restricted nozzle outlet.

The slurry may be delivered to the gun from any suitable source through a flexible line, and the pressure air or gas supplied to the interior of the gun may also be obtained from any convenient source of supply through a flexible line.

By way of example one form of gun in accordance with the invention is illustrated in sectional elevation by the single figure of the accompanying drawing to which reference will now be made.

1 denotes the barrel of the gun in the form of a bent tube the ends of which are externally screw-threaded at 2 and 3. The barrel is equipped with a handle or stock 4 adjacent to which is a trigger 5 pivoted to the barrel at 6 and having its upper end connected by links 7, 7 with a butterfly valve 8 for regulating the supply of slurry through the barrel. The trigger is urged away from the handle 4 by a spring 9 surrounding a pin 9a projecting from the handle.

Threaded on the end 2 of the barrel 1 is a nozzle member 10 having an interchangeable nozzle 11 having a sharply restricted outlet, whilst threaded on the end 3 is a coupling nut 12 by means of which and an adaptor 13 the barrel 1 can be connected to a flexible line 13a leading from a source of slurry supply.

The barrel 1 has a rearward tubular extension 14 terminating at its rear end in a screw-threaded gland 15 for a gland nut 16 with the interposition of a packing 17. A tube 18 is slidable in the extension 14 and in the gland and gland nut. Its forward end projects into the barrel 1 at an adjustable distance from the nozzle 11 and its rear end is equipped with a cock or valve 19 operable

5 by a handle 20. The cock or valve is connectable, by a flexible line not shown, with any suitable source of supply of pressure air or gas.

In the operation of the gun pressure air or gas 10 is admitted via the tube 18 into the front part of the barrel 1 under control of the cock 19, where it acts on the slurry supplied under pressure to the barrel under control of the trigger-actuated butterfly valve 8. The slurry is compacted or 15 densified in the front portion of the barrel between the outlet end of the tube 18 and the sharply restricted outlet of the nozzle 11 and is discharged, by the pressure air or gas, through the said nozzle outlet on to the wall or surface to 20 which the gun is directed.

The distance of the outlet end of the tube 18 from the nozzle 11 is easily and instantly adjustable by sliding the tube forward or backward, to obtain the best results depending on the viscosity 25 of the slurry and the available air or gas pressure.

As shown in the drawing the end of the tube terminates in the accumulating chamber 21 of the barrel 1 at a distance in advance of the baffle wall 11a of the nozzle 11 and the abruptly restricted outlet 11b therein which is not less than 30 twice the diameter of the accumulating chamber whereby mass movement of the compacted or densified slurry is effected under the air or gas pressure. The gland nut 16 serves to lock the pressure tube 18 in an adjusted position.

By means of the gun it is possible to apply slurries rapidly to structural surfaces and to build up the coating to any desired thickness.

After operation and in order to prevent slurry 35 setting in the barrel of the gun and the slurry line, the nozzle 11 may be temporarily closed by any flat surface while pressure air or gas is supplied for a short time through the tube 18 so as to blow back the slurry out of the barrel and 40 slurry line.

If desired a trowel or guide may be combined with the gun to keep the nozzle 11 at a constant distance from the surface being treated.

Reference is made to my copending application 45 Serial Number 775,556, filed September 22, 1947, for Smoothing or finishing trowels for information as to the type of trowel used in the method of my invention, and to my copending application 50 Serial Number 775,555, filed September 22, 1947, for Compositions for surfacing walls, ceilings and the like for a disclosure of the composition and method of finishing surfaces according to my invention.

It is to be understood that modifications may

be made within the scope of the invention as defined by the claims that follow.

I claim:

1. The method of mechanically applying compacted and densified slurry to structural surfaces which consists in accumulating masses of compacted and densified slurry in a confined space and subjecting the accumulated masses of slurry to agitated movement and so forcing the accumulated masses of slurry in an abrupt manner through an orifice to effect a spattering action on the surface being treated.

2. A portable spray gun for applying compacted and densified slurry to structural surfaces comprising a barrel having at one end an inlet for the supply of compacted or densified slurry under pressure and at the other end a discharge nozzle with an abruptly restricted outlet, an accumulating chamber behind said outlet, means adjustable axially of said barrel for introducing air or gas under pressure into the accumulating chamber of the barrel at a position in advance of said abruptly restricted outlet not less than at least twice the diameter of said accumulating chamber, and means for locking the aforesaid means in said adjusted position for discharging compacted or densified slurry from said accumulating chamber.

3. A portable spray gun for applying compacted or densified slurry to structural surfaces comprising a barrel having at one end an inlet for

the supply of compacted or densified slurry under pressure and at the other end a discharge nozzle having an internally screw-threaded orifice therein extending on an axis centrally of said barrel, a substantially cylindrical member externally screw-threaded to engage the internal screw threads in said orifice, said member terminating in abrupt plane surfaces at each end thereof extending substantially normal to the axis of said barrel; said inner abrupt surface constituting a baffle wall, and a pressure tube terminating in an outlet extending in a plane substantially parallel to the said baffle wall of said member and displaced therefrom to allow accumulation of compacted and densified slurry intermediate the baffle wall of said member and the end of said pressure tube whereby the masses of slurry can be successively spattered upon a surface to be treated by sudden pressure ejection through said member.
